UNITED STATES PATENT OFFICE.

LOUIS ARSÈNE DÉSY, OF MONTREAL, QUEBEC, CANADA.

PLOWING-MACHINE.

1,349,821.

Specification of Letters Patent. Patented Aug. 17, 1920.

Application filed July 25, 1919. Serial No. 313,173.

To all whom it may concern:

Be it known that I, LOUIS ARSÈNE DÉSY, residing at 1375 St. Viateur street, in the city of Montreal, in the Province of Quebec, in the Dominion of Canada, have invented certain new and useful Improvements in Plowing-Machines; and I do hereby declare that the following is a full, clear, and exact description of the same.

10 The present invention relates to improvements in plowing machines and its main object is to provide a machine of this character in which a plurality of plows will be carried by the tractor, thus saving time and labor. A further object is to provide a machine of this character of high efficiency and particularly strong and cheap of construction.

15 The invention will be understood with the aid of the accompanying drawings and following description.

In the drawings:

Figure 1 is a side elevation of the machine.

20 Fig. 2 is an enlarged fragmental-side-view of a plow-gear, guides and plow-link.

Fig. 3 is a plan view of the machine, a portion of the plows being broken away, and illustrating the furrows made by the 25 plows.

Fig. 4 is a top view of a single plow and connecting link.

Fig. 5 is a side elevation view of a single plow.

30 Fig. 6 is a rear elevation of the machine.

Fig. 7 is an enlarged detail top view of the sliding frame.

Fig. 8 is a side elevation of the sliding frame.

35 Fig. 9 is an enlarged detail view of the plow-hoisting means.

Fig. 10 is an enlarged cross section on line 10—10 of Fig. 11, the gear having been removed.

40 Fig. 11 is a top view of the chassis of the machine, certain portions being broken away to show the inner arrangement and driving means.

Like numerals of reference indicate corresponding parts in the various figures.

45 In the drawings, 1 is the frame or chassis and is preferably provided at the forward end with the guide wheel 2, the fork of which is rotatably mounted at 3 in the chassis,

sis, and at the rear end with the caterpillar 55 tractor driving mechanism 4, which is provided on each side of the frame 1. The driving wheels of the tractor-chains 4 are preferably driven by the pinions 5 which are mounted on each end of the shaft 6. 60 The shaft 6 is provided intermediate of its length with a differential 7, and 8 is a sprocket wheel operated by the sprocket chain 9 which engages the sprocket 10 rigidly mounted on the shaft 11 suitably 65 journaled in the bearings 12 secured to the frame 1. 13 is a shaft suitably journaled in the bearings 14 provided adjacent said shaft 11 and on which is mounted the pinion 15 which meshes with the gear 16 mounted on the shaft 11. The shafts 13 and 11 are also provided with co-acting speed reducing gears 17 and 18, and 19 is a clutch 70 adapted to disconnect the gears on said shafts 13 and 11. 20 is a bevel gear secured 75 on said shaft 13, and 21 is a beveled pinion adapted to mesh with said bevel gear 20, said pinion 21 being rigidly mounted on the shaft 22 which is connected to the crank shaft 23 of the engine which is not illustrated in the drawings.

The guide wheel 2 is operatively connected to a toothed quadrant 24 which is actuated by the worm 25 which is provided at the end of the shaft 26, and 27 is a friction gear rigidly mounted at the end of said shaft. The shaft 26 is journaled adjacent said friction gear 27 in the bearing 28 which is mounted on the slideable frame 29, said frame being provided with a toothed quadrant 30 which co-acts with the operating rack 31, said rack being operatively connected to a lever 32.

80 The shaft 13 is provided adjacent said friction gear 27 with a right friction gear 85 32 and a left friction gear 33, said gears being adapted to co-act alternately with the gear 27 and thus revolve the shaft 26 to operate the guiding wheel 2 in the right or left direction.

85 Adjacent said gears 32 and 33 and adapted to co-act with said gears, is a friction gear 34 mounted on one end of the shaft 35 which is journaled at one end in the bearing 36 mounted on the bracket 37 and at the other end in the bearing 38 mounted on the movable frame 39 which is provided with a toothed quadrant 40 that co-acts with the 90 100 105

rack 41, said rack being operatively connected to a pedal 42 provided adjacent the steering arm or lever 32^a.

Intermediate of said shaft 35 is rigidly mounted 5 a sprocket 43 which is operatively connected by a sprocket chain 46 to a sprocket 44 which is carried by an internally threaded block 45, and 47 is a threaded rod on which the threaded block 45 is 10 mounted, said rod projecting through one end of said bracket 37 which is also threaded. At one end of said rod 47 are secured two cables 48 and 49 respectively which pass over the double pulley 50 secured to 15 the frame 1, and over the pulleys 51 and 52 secured on the supporting frame 53, said cables being rigidly secured at their outer ends, respectively to the plow frames 54 and 55. The rotation of shaft 35 is transmitted, through sprockets 43 and 44 and 20 chain 46, to the threaded rod 47, which latter is thereby caused to move endwise in one direction or the other with the result that traction is exerted upon or relieved from the 25 cables 48 and 49.

The cables 48 and 49 serve to hoist the plow frames 54 and 55, and 56 indicates a pair of V-shaped brackets, one associated with each of said cables 48 and 49 and located adjacent said frames 54 and 55, said brackets being pivoted at their apices to the main frame or chassis 1 and pivotally connected at the outer ends of their diverging arms to said cables (see Fig. 9) in order to 30 properly balance the weight of the frames 54 or 55 and thus lift them horizontally.

The frame 1 is provided preferably in the rear thereof with slideways 57, and 58 is a frame slidably mounted in said slideways. 40 The said frame 58 is provided with suitable holes 59 at opposite ends thereof in which are rigidly mounted the stub shafts 60, and mounted on said stub shafts 60 are wheels 61 each of which is provided on its inner side with a gear 62. 63 is a brace-member located in rear of said wheels 61 and connecting the rear or outer ends of the stub shafts 60. The wheels 61 are provided with pairs of spaced radially-arranged guides 64 45 around their peripheries, and with projecting lugs 65 located between said guides. The said frame 58 is also provided intermediate thereof with two oblique lugs 66 to which are secured the converging standards 66^a, the 50 uppermost ends of said standards terminating in an upright-member 67 which slides in the guiding-bracket 67^a secured to the upper end of the supporting frame 53. Bearings 68 are provided on said frame 58 in which 55 are journaled the shafts 69. On the rear end of each shaft 69 is mounted the pinion 70 which is adapted to mesh with the adjacent gear 62, and 71 is a gear mounted on the front end of said shaft. 72 are bearings 60 preferably mounted at right angles in

relation to the bearings 68 and supported on the projecting brackets 73 which are integral with said frame 58. In each of said bearings 72 is journaled the shaft 74 provided at opposite ends with pinions 75 which 70 are adapted to mesh with the bevel gears 71, and 76 is a sprocket wheel mounted on said shaft 74. 77 is another sprocket wheel mounted on the driving shaft 13 and connected to the sprocket 76 by means of the 75 sprocket chain 78. It will readily be understood that the rotation of said driving shaft 13 will thereby be imparted to the said wheels 61.

The plow-frames 54 and 55 are provided at their inner ends with collars 79 which encircle the shafts 60, and on the outer ends of said frames are rotatably mounted guide-wheels 80. 81 are supporting wheels which are mounted on the 85 brackets 82, said brackets being rigidly secured at the end of the frames 54 and 55. The frames 54 and 55 are preferably strengthened or braced by the rods 83 which are secured at their lower ends to the 90 brackets 82 and at their upper ends to the frame 1.

84 are a plurality of links flexibly connected together, forming a chain, which passes over said wheels 61 and 80, each of said links 95 84 carrying a plow 85. Each link 84 has a pin 86 projecting downwardly from it and on which is rigidly secured the stub shaft 87, and 88 is a disk-furrower rotatably mounted on said stub shaft 87.

At one side of said plow 85 is mounted an adjustable guide-plate 89 which is provided adjacent each end thereof with a U shaped lug 90 adapted to engage the end of the shaft 87 and the pin 91 secured to one side 105 of said plow side.

As will be seen, the wheels 61 and 80 support the two series of plows 85 carried by the chains 84 which are driven by the gears 62 and pinions 70. Intermediate of said frames 110 54 and 55 are provided the link-supporting-rollers 92 which are rotatably mounted on the brackets 93 secured to the frames 54 and 55.

Secured to the brace-member 63 are a plurality of disk-plows 94 which are pivotally connected to the flexible frames 95, and provided with adjustable tension springs 96. The object of these disk-plows is to fill the space between the two endless series of plows 120 and thus plow the soil between the said series.

The plows 85 provided on the links 84 are preferably disposed at an angle in relation to said links, whereby during the forward movement of the machine a plurality of oblique converging furrows will be made as disclosed in the plan view illustrated in Fig. 3.

The series of plows when they are not in 130

use, may be lifted out of contact with the soil by means of the cables 48 and 49 which are operated by the threaded rod 47, the sprocket wheels 44 and 43, the chain 46, the 5 shaft 35, the rack 41 and the pedal 42.

What I claim as my invention is:

1. In a plowing machine, the combination, with a main frame; of a pair of auxiliary frames disposed at right angles to the main 10 frame with their confronting ends in spaced relation; a connecting bar between said spaced frame ends; an endless series of plows mounted in each auxiliary frame; means for driving said series of plows 15 whereby a plurality of oblique, converging furrows will be made; and a plurality of plows separate from the two endless series of plows suspended from said connecting bar to plow straight furrows in the ground 20 between said endless series of plows.

2. In a plowing machine, the combination, with a main frame; of a pair of auxiliary frames disposed at right angles to the main frame with their confronting ends in spaced 25 relation; a connecting bar between said spaced frame ends; an endless series of plows mounted in each auxiliary frame; means for driving said series of plows whereby a plurality of oblique, converging furrows will be formed; a plurality of 30 plows separate from the two endless series of plows suspended from said connecting bar to plow straight furrows in the ground

between said endless series of plows; and means for raising or lowering both auxiliary 35 frames and the connecting bar and their respective plows from or toward the ground.

3. A plowing machine comprising in combination with a tractor; two endless traveling series of linked plows disposed at right 40 angles in relation to the tractor; a plurality of disk-plows mounted between said series of plows; movable supporting and adjusting means for said series of plows; means to drive said series of plows; and means to 45 lift said series of plows from the soil, substantially as described.

4. In a plowing machine, in combination, two endless series of plows disposed transversely of the machine with their confronting ends in spaced relation; means for driving said series of plows whereby a plurality of oblique, converging furrows will be made; and a plurality of plows separate from the two endless series of plows arranged in the 50 space between the confronting ends of said series to plow straight furrows in the ground which intersect the converging ends of the oblique furrows.

Signed at Montreal, Quebec, Canada, this 60
18th day of June, 1919.

LOUIS ARSENE DÉSY.
